(57) **CLAIM**

The ornamental design for the joiner for conduit for routing cable, as shown.

DESCRIPTION

FIG. 1 is a top, isometric view of a joiner for conduit showing a first embodiment of our new design; FIG. 2 is a bottom, isometric view of a joiner for conduit showing a first embodiment of our new design; FIG. 3 is a front elevation view thereof; FIG. 4 is a rear elevation view thereof; FIG. 5 is a left side elevation view thereof; FIG. 6 is a right side elevation view thereof; FIG. 7 is a top-down plan view thereof; FIG. 8 is a bottom-up plan view thereof; FIG. 9 is a top, isometric view of a joiner for conduit showing a second embodiment of our new design; FIG. 10 is a bottom, isometric view of a joiner for conduit showing a second embodiment of our new design; FIG. 11 is a front elevation view thereof; FIG. 12 is a rear elevation view thereof; FIG. 13 is a left side elevation view thereof; FIG. 14 is a right side elevation view thereof; FIG. 15 is a top-down plan view thereof; FIG. 16 is a bottom-up plan view thereof; FIG. 17 is a top, isometric view of a joiner for conduit showing a third embodiment of our new design; FIG. 18 is a bottom, isometric view of a joiner for conduit showing a third embodiment of our new design; FIG. 19 is a front elevation view thereof; FIG. 20 is a rear elevation view thereof; FIG. 21 is a left side elevation view thereof; FIG. 22 is a right side elevation view thereof; FIG. 23 is a top-down plan view thereof; FIG. 24 is a bottom-up plan view thereof;

(Continued)

FIG. 25 is a top, isometric view of a joiner for conduit for routing cable showing a fourth embodiment of our new design;

FIG. 26 is a bottom, isometric view of a joiner for conduit for routing cable showing a fourth embodiment of our new design;

FIG. 27 is a front elevation view thereof;

FIG. 28 is a rear elevation view thereof;

FIG. 29 is a left side elevation view thereof;

FIG. 30 is a right side elevation view thereof;

FIG. 31 is a top-down plan view thereof; and,

FIG. 32 is a bottom-up plan view thereof.
